UNITED STATES PATENT OFFICE.

FRANCIS J. TORRANCE, OF ALLEGHENY, PENNSYLVANIA, ASSIGNOR TO
STANDARD SANITARY MANUFACTURING COMPANY, OF ALLEGHENY,
PENNSYLVANIA, A CORPORATION OF PENNSYLVANIA.

DESIGN FOR A LAVATORY.

SPECIFICATION forming part of Design No. 35,730, dated February 11, 1902.

Application filed October 10, 1901. Serial No. 78,276. Term of patent 7 years.

To all whom it may concern:

Be it known that I, FRANCIS J. TORRANCE, a citizen of the United States, residing at Allegheny, in the county of Allegheny and State of Pennsylvania, have invented and produced a certain new and original Design for a Lavatory; and I do hereby declare the following to be a full, clear, and exact description of the invention, such as will enable others skilled in the art to which it appertains to make and use the same.

My design for a lavatory is shown in the accompanying drawings, in which—

Figure 1 is a perspective view, Fig. 2 a plan view, and Fig. 3 a transverse sectional view, of the lavatory.

The design is for a lavatory in which the bowl A, slab B, and apron C are of the configuration shown in the drawings; and the es-

sential element of the design is the continuous 20 flat-faced depending apron C, shaped and finished at the back to correspond with the shape and finish of the sides and front and like the front joined to the sides by the rounded corners, thus forming a lavatory-top complete 25 in itself. The slab B has a raised border or bead a, and the walls of the apron C flare outward slightly toward the lower edge, which is headed or flanged, as shown at d.

What I claim as my invention is—

The design for a lavatory as herein shown and described.

In testimony whereof I affix my signature in presence of two witnesses.

FRANC. J. TORRANCE.
